(57) **CLAIM**

The ornamental design for an auxiliary clip-on for eyeglasses, as shown and described.

DESCRIPTION

FIG. 1 is a side, perspective view of the auxiliary clip-on for eyeglasses of the present invention, with the lenses illustrated in phantom lines as not forming a part of the claimed design; FIG. 2 is a side, perspective view thereof without the lenses shown in FIG. 1;

FIG. 3 is a front view thereof;

FIG. 4 is a rear view thereof;

FIG. 5 is a top view thereof;

FIG. 6 is a bottom view thereof; and,

FIG. 7 is a left side view thereof, the right side being a mirror image thereof.
